UNITED STATES PATENT OFFICE.

CHARLES E. HOPKINS, OF PLAINFIELD, NEW JERSEY.

CONVEYER FOR CURVED STEREOTYPE PRINTING-PLATES.

1,286,883.

Specification of Letters Patent.

Patented Dec. 3, 1918.

Application filed October 28, 1912, Serial No. 728,149. Renewed November 30, 1917. Serial No. 204,787.

To all whom it may concern:

Be it known that I, CHARLES E. HOPKINS, a citizen of the United States, formerly residing at New York, in the county of New York and State of New York, but later residing at Plainfield, county of Union, and State of New Jersey, have invented a new and useful Conveyer for Curved Stereotype Printing-Plates, of which the following is 10 a specification.

This invention relates to means for delivering a curved stereotype printing plate that is cast in vertical position in a straight line to a horizontal finishing means with its 15 convex side up.

The principal objects of the invention are to provide a simple form of conveying device adapted to receive a semi-cylindrical plate in position with its convex side down 20 and turn it over into a reverse position so as to apply the concave side of the plate to a rotary finishing cylinder axially aligned with the plate in said position whereby the plate can be given a substantially continued motion; and to provide means in connection 25 therewith for supporting and automatically releasing it when it rests on the cylinder so as to permit the conveying means to be moved back in position for receiving another 30 plate. Further features and advantages of the invention will appear hereinafter.

Reference is to be had to the accompanying drawings in which—

Figure 1 is a side elevation of a casting and finishing machine showing a preferred form of this invention applied thereto with the conveying frame part way between its two extreme positions and a part of the front side frame removed;

Fig. 2 is a plan of the same showing the conveying frame at its extreme position in the casting back with part of the finishing cylinder broken away to show details of construction;

Fig. 3 is an end view thereof showing the driving mechanism; and

Fig. 4 is an end view with part of the frame removed to show the way in which the plate is delivered to the finishing cylinder and released.

The invention is shown as used in connection with a casting mechanism of a form which is not shown herein in full as it forms the subject matter of my Patent 1,268,463, 5 dated June 4, 1918, on a machine for mak-

ing stereotype printing plates. This casting mechanism involves a vertical stationary core A fixed on a frame B. In front of the convex face of the core is a concave back C which is supported by rollers D and E operating on tracks F and G formed on the side frames of the base, and at each side of the core. As set forth in my above mentioned application the movement of this back toward the core causes the rollers E to run 60 down the vertically inclined tracks G and the rollers D to run along the horizontal track F. This causes the back to turn from horizontal position to a vertical one against the core in position for casting. The means 65 for holding the parts in this position is not shown herein as it forms no part of the present invention. After a plate is cast the operator turns the back away from the core into horizontal position as shown in Fig. 1. 70

According to the present invention this concave back is provided with a transverse shaft 10 at one end and at the top thereof when it is in horizontal position. On this shaft is fixed a plate conveying frame consisting of two side members 11 adapted to be turned by the shaft through the operation of the handle 12 thereon, against the concave back so as to lie along the straight sides thereof. These side members are 80 joined together at the end opposite the shaft by a half ring 13 which is provided with the usual bevel for forming a bevel at the bottom of the plate when cast. A thin metal pouring sheet 15 is arranged on the conveying frame near the shaft 10 so as to overlap 90 a portion of the concavity of the back as is well understood in the art.

Each of the side members of the conveying frame is provided with a hinged casting 95 bar 16 for the purpose of forming the side walls between the core and back, and also for the purpose of holding the straight edges of the matrix in position in the casting chamber. It will be seen that when the 100 parts are in position in the back these side members engage the straight edges of the plate and when the lever 12 is operated to swing the frame and plate over as indicated in Fig. 1, these side members are prevented 105 from swinging on their hinges by the plate itself. Consequently, they support the plate during its swinging motion after it passes vertical position. When this operation is performed the matrix of course is 110

left in the back ordinarily. When the plate carrying frame reaches a reverse horizontal position the plate, still held by the side bars, will be brought into contact with a horizontal rotatable finishing cylinder H. When this occurs the weight of the plate of course is supported by the cylinder and the side bars are relieved from the pressure of the plate. Consequently they are free to swing 5 downwardly by gravity as shown in Fig. 4. This automatically frees them from the plate and the conveying frame can be swung back immediately, leaving the plate resting 10 on the finishing cylinder. The axis of the cylinder H is in alignment with the axis of the back when in delivering position.

The finishing mechanism illustrated is driven by a driving pulley 30 on a main shaft 31. This pulley is connected with the shaft by clutch jaws 32 and 33, one fixed to 20 the shaft and the other to the pulley. A starting bar 34 is provided pivoted at 35 and provided with a pin 36 entering a groove in the clutch jaw 32 on the pulley 25 for swinging the clutch jaw into engagement with the other one and starting the shaft. On this shaft is a worm 37 which meshes with a worm gear 38 fixed to the axle of the cylinder to drive it directly. 30 Fast on the driving shaft is a bevel gear 40 meshing with a smaller bevel gear 41 fixed to a horizontal saw shaft 42 on which is a tail-cutting saw 43 located so as to separate the tail portion of the plate from the 35 type portion as the cylinder revolves with the plate thereon.

For the purpose of holding the plate against the cylinder while being revolved there are provided a series of freely rotatable horizontal rollers 46 located at the proper distance from the face of the cylinder to engage the face of the stereotype plate and support it against the cylinder during its rotation. These rollers are covered with 40 felt 56 or other yielding substance so as not to injure the type face of the plate. For the purpose of holding the plate on the cylinder and permitting it to be rotated in this way, the cylinder is provided with a set of 45 tapered pins 45 adapted to enter tapered holes 47 in the under side of the cast plate formed by tapered pins 48 on the convex face of the core.

When the rotation of the cylinder is completed, a pin 50 on the face of the worm gear 55 38 comes into contact with a projection 51 formed on the starting bar 34 and moves the starting bar back to inoperative position, thereby stopping the machine.

It will be understood, of course, that this 60 invention can be used with other types of casting and finishing machines than those illustrated herein, and that many changes in the details of construction can be made 65 within the scope of the claims. Therefore

I do not wish to be limited in these respects but what I do claim is:—

1. The combination with means for supporting a curved stereotype printing plate with the concave side up, of means in axial alignment therewith for receiving said plate with the concave side down, and means for moving the plate from the first named means to the second.

2. The combination with a concave support 75 for a curved stereotype casting plate, of a plate conveying frame pivoted on a transverse axis to one end of said support and movable about its pivot from the support to a position in axial alignment with the support for delivering the plate therefrom.

3. The combination with a casting mechanism having means for delivering a plate in horizontal position with its concave side 85 up, and a finishing mechanism having a finishing cylinder for receiving the plate, the axis of said cylinder being in alignment with the axis of the plate when ready for delivery from the casting mechanism, and 90 means for moving the plate from the casting mechanism to said cylinder.

4. The combination with a casting machine adapted to deliver a curved stereotype printing plate in horizontal position 95 with its concave side up, and a finishing machine in axial alignment therewith adapted to receive the curved plate with its concave side down, of means for swinging the plate over on a transverse axis at its end 100 from the casting mechanism to the finishing mechanism and depositing it on the latter.

5. The combination with a device for casting a curved stereotype printing plate in 105 vertical position and turning it over to horizontal position with its concave side up, and a finishing machine in alignment endwise with the position of the plate when turned away from the casting position, of means for swinging the plate over end for end 110 from said vertical position into the finishing machine.

6. The combination with a casting mechanism comprising a movable concave back, and means for supporting the back in horizontal position with its concave side up, a 115 finishing cylinder having its axis in the same vertical plane as the axis of said back for receiving a concave plate on its cylindrical surface in alignment with said back, and 120 means for swinging a plate from the back to the cylinder and leaving it thereon, said means comprising a frame pivoted to the end of said casting back and adapted to rest in the back during the casting operation.

7. The combination with a casting mechanism comprising a movable concave back, and means for supporting the back in horizontal position with its concave side up, of 125 a finishing cylinder for receiving a concave 130

plate on its cylindrical surface in longitudinal alignment with said back, a frame pivoted to the end of said back and adapted to rest in the back during the casting operation

5 and to swing into position over said cylinder, and longitudinally hinged oppositely swinging casting bars at the edges thereof adapted to support the plate while the frame swings over the cylinder.

10 8. The combination with a concave support for a curved stereotype printing plate, of a plate conveying frame pivoted to one end of said support and movable about its pivot from the support to a position in alignment with the support for delivering the plate therefrom, said frame being provided with a pair of bars longitudinally and independently hinged to its straight edges for resting on the plate while on said support and supporting the plate when the frame moves over to reverse position.

9. The combination with a concave support for a curved stereotype printing plate, of a plate conveying frame pivoted to one end of said support and movable about its pivot from the support to a position in alignment with the support for delivering a cast plate therefrom, said frame being provided with a pair of bars longitudinally and separately hinged to its straight edges for resting on the plate while on said support and supporting the plate when the frame moves over to reverse position, and a cylindrical member for receiving the plate

35 in position to support the weight of the plate as the frame moves into its horizontal position and release said bars so as to permit them to swing downwardly on their hinges.

10. The combination of a pivoted plate carrying frame for carrying a semi-cylindrical stereotype printing plate having a pair of bars longitudinally and individually hinged thereto at the outer edges of said bars and adapted to project up into the frame to support the edges of a plate, and means for receiving said plate from the frame when it is turned over to horizontal position and supporting the plate whereby

said bars will be released from the plate and swing downwardly by gravity about their 50 hinges.

11. The combination with a support for a stereotype printing plate, of a plate conveying frame pivoted to said support and movable about its pivot from the support 55 to a position for delivering the plate therefrom, said frame being provided with a pair of bars longitudinally and independently hinged to its edges resting on the plate while on said support and supporting the plate 60 when the frame moves over to reverse position, said bars being arranged to swing inwardly toward each other by gravity.

12. The combination with a support for a printing plate, of a plate conveying frame 65 arranged to be turned over, said frame having a pair of plate supporting bars hinged thereto along their outer edges and capable of being swung inwardly to engage and hold the plate when the frame is turned over, 70 said bars normally swinging down by gravity out of contact with the plate when the frame is inverted and the plate is otherwise supported.

13. The combination with a support for a 75 printing plate, of a plate conveying frame arranged to be turned over, said frame having a pair of parallel plate supporting bars independently hinged thereto along their outer edges and capable of being swung inwardly to engage and hold the plate when the frame is turned over, whereby the plate holds the bars from swinging downwardly, and means in position for receiving the plate at the end of the travel of the frame, 80 relieving the bars from the weight of the plate, and freeing them, whereby they will automatically swing down.

In testimony whereof I have hereunto set my hand, in the presence of two subscribing 90 witnesses.

CHARLES E. HOPKINS.
